[57] CLAIM

The ornamental design for a tire, as shown and described.

DESCRIPTION

FIG. 1 is a perspective view of a tire showing my new design, it being understood that the tread pattern is repeated throughout the circumference of the tire, the opposite side being substantially the same as that shown; FIG. 2 is a front elevational view thereof; FIG. 3 is a side elevational view thereof on a reduced scale; and

FIG. 4 is an enlarged fragmentary front elevational view thereof.

FIG. 1

FIG.2

FIG.3

FIG.4

UNITED STATES PATENT AND TRADEMARK OFFICE
CERTIFICATE OF CORRECTION

PATENT NO. : Des. 316,842
DATED : May 14, 1991
INVENTOR(S) : Maurice I. Graas

It is certified that error appears in the above-identified patent and that said Letters Patent is hereby corrected as shown below:

Title page, item (75):

Remove the middle initial "I" from the inventor's name.

There is no middle initial.

Signed and Sealed this

Fifteenth Day of September, 1992

Attest:

DOUGLAS B. COMER

Attesting Officer

Acting Commissioner of Patents and Trademarks
